United States Patent Office

Des. 229,374
Patented Nov. 20, 1973

229,374

PHOTOGRAPHIC ALBUM

Jay I. Sher, 271 S. Beverly Drive,
Beverly Hills, Calif. 90212

Filed June 14, 1971, Ser. No. 153,141

Term of patent 14 years

Int. Cl. D19—04

U.S. Cl. D97—2

FIG. 2

FIG. 3

FIG. 4

FIG. 5

FIG. 1

FIG. 6

FIG. 7

FIG. 1 is a top perspective view of a photographic album showing my new design;

FIG. 2 is a top plan view thereof;

FIG. 3 is a bottom plan view;

FIG. 4 is a bottom end view;

FIG. 5 is a top end view;

FIG. 6 is a side elevational view as seen from the left of FIG. 2; and

FIG. 7 is a side elevational view as seen from the right thereof.

I claim:

The ornamental design for a photographic album, as shown and described.
